(57) **CLAIM**

The ornamental design for a combined shaving razor cartridge and cover, as shown and described.

DESCRIPTION

FIG. 1 is a first perspective view of a design of a combined shaving razor cartridge and cover of the present invention; FIG. 2 is a top view thereof; FIG. 3 is a bottom view thereof; FIG. 4 is a left side view thereof; FIG. 5 is a right side view thereof; FIG. 6 is a rear view thereof; FIG. 7 is a front view thereof; and, FIG. 8 is a second perspective view thereof.

The dash broken lines are directed to portions of the combined shaving razor cartridge and cover and form no part of the claimed design.

1 Claim, 6 Drawing Sheets
